UNITED STATES PATENT OFFICE.

LOUIS V. ARONSON, OF NEWARK, NEW JERSEY, ASSIGNOR TO VOICES INCORPORATED,
A CORPORATION OF DELAWARE.

SOUND DEVICE.

Application filed February 7, 1924. Serial No. 691,103.

My invention relates to improvements in sound devices and is especially adapted for sound devices to be inserted in dolls and other devices to utter therein sounds like 5 ma-ma, pa-pa, etc.

The main object of the invention is to provide a more simple and efficient device of this character and which occupies relatively little space and yet may be easily and 10 cheaply constructed. Further and more specific objects, features and advantages will more clearly appear from the detail description given below taken in connection with the accompanying sheet of drawings 15 which form a part of this specification.

In the drawings Fig. 1 is a section through a device embodying my improvements in a preferred form and showing the bellows member therein collapsed. Fig. 2 is a 20 similar view illustrating the bellows member in the device distended. Fig. 3 is a transverse section taken on the line 3-3 of Fig. 1.

Referring to the drawings, 4 represents a cylinder container made of thick cardboard or any other suitable material. Secured to 25 one end of the cylinder by a circular flange 5 is a cap member 6 which covers the end of the cylinder except for perforations 7 therein. Slidable axially within the cylinder 4 is a sound chamber comprising a circular inverted cup shaped member or cap 8, preferably of sheet metal. The lower side 30 of the cup shaped member is closed by a relatively thick heavy dished member 9, the periphery of which tightly fits within the mouth of the cup shaped member so that it is rigid therewith. The metallic member 9 is provided with a deep circular groove on 35 its lower side as viewed in Fig. 1 and a depression encircled by said groove on the other side. Wedged into the outer dished portion of the member 9 is disc member 10. Between the periphery of the disc 10 and 40 the inside surface of the downwardly extending flange at the outer edge of the member 9, is peripherally secured at 12, the upper end of a tubular bellows member 11, made of rubberized cloth or other suitable 45 material. The other end of the tubular bellows member is peripherally secured to the lower end of the cylinder 4 at 13 by being swedged thereagainst by the peripheral flange 14 on a sheet metal cap member 15 50 which closes the lower end of the cylinder 4.

Extending an aperture through the member 9 and lying within the deep circular groove in the member 9 is a reed pipe 15 provided with a sound reed at 16. The member 10 is cut away at 17 to accommodate the 60 lower end of the reed pipe and reed. The member 10 is also cut away at 18 to accommodate the downwardly projecting portion 19 accommodating the aforesaid depression in the member 9. Secured to the cap 6 as 65 by nails or screws 20 is a cylindrical knob or control member 21, preferably made of wood and provided with a peripheral circular groove at 22. With the bellows member distended and the parts as shown in Fig. 2, 70 the knob 21 extends through a circular aperture 23 in the top of the sound chamber 8, and the end of the knob is seated on downwardly projecting seat 19 forming the bottom of said depression in the member 9. 75

In operation, with the parts as shown in Fig. 2, the sound chamber comprising the parts 8, 9 and 10 will fall by gravity due to the weight of the parts and particularly of the member 9. The circular sound chamber, therefore, slides axially of cylinder 4. The circular periphery of the sound chamber member 8 lies closely adjacent the inside circular wall of the cylinder 4 so that the sound chamber slides on and is guided solely by 80 the inside wall of the cylinder on its movement back and forth in the cylinder. When the sound chamber thus falls under the action of gravity the bellows member 11 collapses thus causing the air therein to be forced out through the reed pipe causing 85 the reed to speak and produce the sound thereof in the sound chamber within the cup-shaped member 8. During the first part of the movement no sound is audible due to the fact that the sound chamber is substantially closed to the outside, the knob 21 substantially closing the opening 23. When, however, the opening 23 comes opposite the groove 22 on the knob the reed will audibly 90 speak, the sound coming out through the opening 23 around the groove 22. Upon further downward movement of the sound chamber the lower end of the knob 21 substantially closes the opening 23 thereby interrupting the sound from the reed pipe. Upon 95 further downward movement of the sound chamber as viewed in Fig. 2, the knob will be entirely removed from the opening 23 thereby again rendering audible the sound 100 105 110

from the reed pipe. The last movement is relatively long as compared with first sounding movement whereby the device is caused to utter two sounds like "ma-ma" or "pa-pa", the latter syllable of which is of longer duration than the first. The parts finally assume the position shown in Fig. 1. Upon turning the device upside down gravity will cause the sound chamber to return to the opposite end of the cylinder so that the parts will assume the position shown in Fig. 2. The device is then ready for a second similar operation. When placed in a doll the movements are caused by reversing the position of the doll in a manner well understood by those skilled in the art.

While I have described my improvements in great detail and with respect to a preferred form thereof, I do not desire to be limited to such details or form since many changes may be made and the invention embodied in widely different forms without departing from the spirit and scope of the invention in its broader aspects. Hence I desire to cover all modifications and forms coming within the language or scope of any one or more of the appended claims.

What I claim as new and desire to secure by Letters Patent, is:

30 1. A sound device having in combination a cylinder, a sound chamber mounted to slide axially of the cylinder therein, the periphery of said sound chamber lying closely adjacent the inside wall of the cylinder where-
35 by the sound chamber is guided in its move-
ment by the inside wall of the cylinder, means closing one end of the cylinder, a tubular bellows member having one end there-
of connected to the closed end of the cylin-
40 der, and the other end connected to the sound chamber, a sound reed operatively connected with the sound chamber whereby upon movement of the sound chamber said reed is caused to speak, and valve means co-
45 operating with an aperture in said sound chamber to interrupt the sound produced therefrom during movement of the said chamber in the cylinder, said valve means comprising a grooved knob secured to the other end of the cylinder and adapted to enter said aperture.

2. A sound device having a compressible air chamber with a movable weighty head acting to compress said chamber by gravity, said head comprising a member having a deep circular groove on one side and a depression on the other side encircled by said groove, said member having an aperture therethrough at said groove, a reed pipe situated within said groove and cooperating with said aperture and a cap member secured to said member and forming therewith a sound chamber on one side thereof into which the sound from the reed is adapted to issue.

3. A sound device having a compressible air chamber with a movable weighty head acting to compress said chamber by gravity, said head comprising a member having a deep circular groove on one side and a depression on the other side encircled by said groove, said member having an aperture therethrough at said groove, a reed pipe situated within said groove and cooperating with said aperture and a cap member secured to said member and forming therewith a sound chamber on one side thereof into which the sound from the reed is adapted to issue, said cap member having an opening into the sound chamber, and a control member adapted to slide in and out of said opening to control the issuance of sound therefrom, said first mentioned member being imperforate to said control member.

4. A sound device having in combination a container closed at one end, a sound chamber slideable back and forth in the container, a bellows member one end of which is secured to the closed end of the container and the other end of which is secured to the movable sound chamber to form a bellows to be collapsed and distended by movement of the sound chamber in the container, a sounding means operatively associated with said sound chamber to produce sound therein upon operation of the bellows by movement of the sound chamber, and a control member secured to the opposite end of the container and adapted to slide in and out of an opening in the side of the sound chamber opposite the closed end of the container, the bellows side of the sound chamber being imperforate to said control member.

5. A sound device having in combination a container closed at one end, a sound chamber slideable back and forth in the container, a bellows member one end of which is secured to the closed end of the container and the other end of which is secured to the movable sound chamber to form a bellows to be collapsed and distended by movement of the sound chamber in the container, a sounding means operatively associated with said sound chamber to produce sound therein upon operation of the bellows by movement of the sound chamber, and a control member secured to the opposite end of the container and adapted to slide in and out of an opening in the side of the sound chamber opposite the closed end of the container, the bellows side of the sound chamber being imperforate to said control member, and said control member being adapted to interrupt the sound from the sound chamber as it slides through said opening in the side of the sound chamber.

6. A sound device having in combination a container closed at one end, a sound chamber slideable back and forth in the container, a bellows member one end of which is secured

to the closed end of the container and the other end of which is secured to the movable sound chamber to form a bellows to be collapsed and distended by movement of the 5 sound chamber in the container, a sounding means operatively associated with said sound chamber to produce sound therein upon operation of the bellows by movement of the sound chamber, and a control member secured 10 to the opposite end of the container and adapted to slide in and out of an opening in the side of the sound chamber opposite the closed end of the container, the bellows side of the sound chamber being imperforate to said control member, and the 15 periphery of the sound chamber lying closely adjacent the inside wall of the container whereby it slides upon and is guided by said inside wall.

20 7. A sound device having a compressible air chamber with a movable weighty head acting to compress said chamber by gravity, said head comprising a formed member having a deep circular groove on one side and a 25 depression on the other side encircled by said groove, a cover member secured to said formed member on the side of the depression forming therewith a sound chamber, the formed member having an aperture there- 30 through serving as an air passage between the interior of the air chamber and the sound chamber, a reed associated with the aperture

and adapted to be sounded by the current of air through the aperture during the movement of the weighty head. 35

8. A sound device comprising a tubular container closed at one end, a sound chamber slidable back and forth in the container, sounding means operatively associated with the sound chamber to produce sound therein, said sound chamber having an opening in one side thereof, and a control member secured with respect to the opposite end of the container and adapted to slide in and out of said opening, the opposite side of the 40 sound chamber being imperforate to said control member. 45

9. A sound device comprising a tubular container closed at one end and having a perforated closure at the opposite end, a sound 50 chamber slidable back and forth in the container, sounding means operatively associated with the sound chamber to produce sound therein, said sound chamber having an opening in one side thereof, and a control mem- 55 ber secured to the perforated end closure of the container and adapted to slide in and out of said opening, the opposite side of the sound chamber being imperforate to said control member. 60

In testimony whereof I have signed my name to this specification.

LOUIS V. ARONSON.
